ATTORNEY.

UNITED STATES PATENT OFFICE

2,329,967

SUPPORTING STRUCTURE FOR FLOATING
TANK ROOFS

John H. Wiggins, Chicago, Ill.

Application February 12, 1942, Serial No. 430,532

2 Claims. (Cl. 220—26)

This invention relates to liquid containers of the type that are equipped with a floating roof, and particularly, to the means used in such structures for supporting or sustaining the weight of the roof when the roof is not floating on liquid in the container.

One object of my invention is to provide an improved auxiliary supporting structure for a floating roof, which is of such design that when cleaning of the container becomes necessary, said auxiliary supporting structure can be adjusted or manipulated so as to cause the roof to be sustained at a level high enough above the bottom of the container to provide ample clearance for workmen engaged in the operation of removing sediment that has collected on the bottom of the container.

Another object is to provide a supporting means for a floating tank roof, that has provision for sustaining the roof in either one of two different levels when the tank is empty, or substantially empty, and which can be properly adjusted or manipulated while the roof is floating on liquid in the tank, so as to select the particular level at which it is desired to support the roof, when the liquid is discharged from the tank.

And still another object of my invention is to provide a floating tank roof that is equipped with a plurality of horizontally-slidable, auxiliary supports that are mounted on the roof in such a way that they are operable from the top side of the roof, but nevertheless, are hidden from view and protected from the weather. Other objects and desirable features of my invention will be hereininafter pointed out.

Figure 1 of the drawing is a vertical transverse sectional view of a pontoon type floating roof constructed in accordance with my present invention, showing the roof floating on liquid in the container, and illustrating the horizontally-slidable, auxiliary supports arranged in their inactive position.

Figure 2 is a similar view, showing the roof floating on the liquid, and illustrating the auxiliary supports in their active position.

Figure 3 is a vertical, transverse sectional view, illustrating how said horizontally-slidable, auxiliary supports co-act with the fixed or stationary supporting structure inside of the container to maintain the roof high enough above the bottom of the container to provide ample head room or clearance for workmen engaged in the operation of cleaning the container; and

Figure 4 is an enlarged sectional view, taken on

the line 4—4 of Figure 2, looking in the direction indicated by the arrows.

In the accompanying drawing which illustrates the preferred form of my invention, A designates a liquid container, such as an oil storage tank, and B designates as an entirety a floating roof which normally floats upon liquid x in the tank, said roof comprising a limber metal deck 1 that is attached to the upper end of an annular pontoon C located at the periphery of the roof.

My invention consists of a supporting means for the roof B, which is of such construction that it will sustain the roof at either one of two different levels when the tank is empty or not 5 filled with sufficient liquid to float the roof. One of said levels constitutes the lowermost position of the roof, and the other level constitutes the position of the roof when the bottom of the tank is being cleaned to remove sediment that has collected thereon. Preferably, the roof is sustained in its lowermost position, or at the low level, by a fixed or stationary supporting structure D in the lower portion of the tank A, disposed so that the pontoon C of the roof will come to rest thereon 10 when the level of the liquid in the tank drops to a point below the top surface of said supporting structure D. The particular construction of the supporting structure D is immaterial. It may consist of short standards or uprights that project upwardly from the bottom of the tank A in proximity to the side wall of the tank, or it may consist of a framework on the bottom of the tank that extends circumferentially around the tank adjacent the tank side wall. The roof is sustained 15 at the high level or in tank cleaning position, by a plurality of horizontally-slidable, auxiliary supports E on the roof, that are adapted to be shifted into a position wherein they co-act with the fixed or stationary supporting structure D, to in effect 20 increase the height of same, or in other words, form upwardly-projecting extensions on the stationary supporting structure D, on which the pontoon of the roof comes to rest, during the operation of emptying the tank, thereby causing the roof to be supported high enough above the bottom of the tank to provide ample head room for workmen engaged in cleaning the tank.

The horizontally-slidable, auxiliary supports E can be mounted on the roof B in various ways without departing from the spirit of my invention, but I prefer to suspend them from the underside of the roof in such a manner that they are operable from the top side of the roof when the roof is floating, and can be easily shifted from a normally inactive position into an active

position, wherein they are disposed underneath the pontoon C of the roof. When the auxiliary supports E are in their inactive position, shown in Figure 1, they are disposed out of vertical alignment with the pontoon C of the roof and the fixed or stationary supporting structure D inside of the tank, and accordingly, do not interfere with the rise and fall of the roof, in response to variations in the level of the liquid x on which the roof floats. Also, when the level of the liquid drops to such a point that the pontoon of the roof moves downwardly onto the fixed or stationary supporting structure D, the auxiliary supports E do not interfere with the downward movement of the roof, due, of course, to the fact that said auxiliary supports E lie in a different vertical plane than the plane in which the pontoon C and stationary supporting structure D are disposed. When it becomes necessary to remove sediment that has collected on the bottom of the tank A, the auxiliary supports E are shifted horizontally into their active position, as shown in Figure 2. Subsequently, when the liquid x is discharged from the tank to empty the tank, the roof moves downwardly until the auxiliary supports E come in contact with the stationary supporting structure D, thereby causing the roof to be supported or sustained at a level high enough above the bottom of the tank, as shown in Figure 3, to provide ample head room or clearance for the workmen engaged in the operation of cleaning the tank.

In the form of my invention herein illustrated, each of the auxiliary supports E is suspended from a horizontally-disposed carrier 2 that slides in bearings on the underside of the roof. In order that the auxiliary supports E may be readily moved into and out of their active position, while the roof is floating on the liquid in the tank, the carriers 2 are slidably mounted in bearings 3 carried by the inner vertical wall of the pontoon C and bearings 3a that project downwardly from the underside of the deck 1 of the roof in spaced relationship with the bearings 3, and the pontoon C is provided in its top wall with manholes 4 that are normally closed by removable manhole covers 5, the carriers 2 being so arranged that they can be manipulated from the interior of the pontoon to shift the supports E horizontally into and out of their active position.

Each of the horizontally-reciprocating carriers 2 is provided with a depending rod or leg 6 to which one of the auxiliary supports E is attached, and said auxiliary supports are preferably formed from hollow members that have some buoyancy, as I have found that this type of construction is desirable, inasmuch as the buoyant auxiliary supports E exert little or no load on the reciprocating carriers 2, and accordingly, do not retard the free sliding movement of the carriers in their bearings. The carriers 2 preferably consist of flat or square bars, as shown in Figure 4, which, on account of their rectangular cross-sectional shape, eliminate the possibility of the auxiliary supports E assuming an angular position with relation to the pontoon C, or the stationary supporting means D. In order to eliminate friction between the auxiliary supports E and the bottom of the pontoon C when said auxiliary supports are shifted into and out of their active position, said auxiliary supports are suspended from their carriers 2 by rods or bars 6 that are slightly flexible and which are made of such length that when the auxiliary supports are shifted laterally into vertical alignment with the pontoon C, the upper

5 ends of said auxiliary supports will be spaced slightly away from the bottom of the pontoon C, as shown in Figure 2. Subsequently, when the roof moves downwardly, the rods or bars 6 will flex sufficiently to permit the bottom of the pontoon to contact with the upper end of the auxiliary supports E, and thus cause the weight of the roof to be transmitted directly to the fixed or stationary supporting means D by the auxiliary supports E. In order to prevent gases from escaping from the gas space of the tank through the bearings 3 in the inner side wall of the pontoon C, said bearings 3 are provided with removable closures 7 which normally are mounted on or combined with said bearings 3 in such a way as to close the openings in the side wall of the pontoon through which the carriers 2 project into the interior of the pontoon.

From the foregoing it will be understood that the auxiliary supports E are normally set or adjusted in the position shown in Figure 1. At such times the fixed or stationary supporting structure D in the tank sustains the weight of the roof whenever the level of the liquid x drops low enough to cause the pontoon of the roof to rest upon said supporting structure D. If cleaning of the tank becomes necessary, the manhole covers 5 of the pontoon are removed, as shown in Figure 2, so as to permit the closures 7 of the bearings 3 to be taken off, after which the carriers 2 are moved in a direction to shift the auxiliary supports E into operative relationship with the pontoon to cause the roof to be sustained at a level considerably higher than the level at which the roof lies when the pontoon of the roof rests directly upon the stationary supporting structure D. When the roof is in this position, ample clearance or head room is provided for the workmen inside of the tank who are engaged in the operation of cleaning the tank. At the completion of the cleaning operation, liquid is again admitted to the tank, and after the liquid level has become high enough to float the roof, the auxiliary supports E are slid horizontally back to their inactive position and the closures 7 are replaced on the bearings 3 in the side wall of the pontoon.

One decided advantage of a tank roof supporting structure of the kind above described, is that the operator who adjusts or manipulates it is not apt to make a mistake and set the auxiliary supports in their "inactive" position, when he intended that said supports should be set in their "active" position. This is because said auxiliary supports are fastened to horizontally-slidable carriers that are mounted on the roof in such a manner that when the operator pulls said carriers towards him, or, in other words, slides said carriers outwardly towards the side wall of the tank, he knows that the auxiliary supports will move into their active position in vertical alignment with the pontoon of the roof, and when he pushes said carriers away from him, or pushes them inwardly towards the center of the tank, he knows that the auxiliary supports will be shifted out of the zone of the pontoon into their inactive position.

Another desirable feature or characteristic of my improved construction, is that it does not rely on gravity or on a separate stop block attached to the roof, to determine or control the active position of the auxiliary support. It is the inner side wall or rim of the pontoon that governs the active position of the auxiliary supports, and said supports are fastened to hori-

zontally-slidable carriers, which are of such cross-sectional shape, that they cannot twist or turn, and thus cause the auxiliary supports to assume an improper position. In addition to the above mentioned desirable characteristics, my improved construction is of rugged design, it is easy to install, and the auxiliary supports are hidden from view and well protected from the weather.

Having thus described my invention, what I claim and desire to secure by Letters Patent is:

1. A floating tank roof, comprising a limber deck attached to the upper end of an annular pontoon located at the periphery of the roof, horizontally-disposed reciprocating carriers arranged on the underside of the deck and slidably mounted in bearings in the inner side wall of said pontoon, rods projecting downwardly from said carriers, and buoyant auxiliary supports attached to said rods, said carriers being adapted to be actuated to shift said auxiliary supports into and out of vertical alignment with said pon-

toon and said pontoon being provided with means that provides access to said carriers.

2. The combination of a liquid container, a floating roof in said container provided at its periphery with a depending pontoon, stationary supporting means for sustaining the roof in comparatively close proximity to the bottom of the container when the roof is not floating, and horizontally-slidable, auxiliary supports on the underside of the roof, normally spaced away from the inner edge portion of the pontoon of the roof but adapted to be moved under the inner edge portion of said pontoon to co-operate with same and with said stationary supporting means, to sustain the roof at a higher level than the level at which the roof lies when it is sustained by said stationary supporting means, said auxiliary supports being suspended from horizontally-reciprocating carriers on the underside of the roof that slide in bearings in the side wall of said pontoon.

JOHN H. WIGGINS.
